(57) **CLAIM**

The ornamental design for a charging stand as shown and described.

DESCRIPTION

FIG. 1 is a perspective view of a charging stand showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof showing the batteries plugged in the charging stand.

The broken lines showing the batteries in FIG. 8 is for the purpose of illustrating environmental structure, and form no part of the claimed design. All other broken lines depict portions of the charging stand that form no part of the claimed design. Unshaded surfaces form no part of the claimed design.

1 Claim, 8 Drawing Sheets
